UNITED STATES PATENT OFFICE.

FREDERICK W. MEYER, OF LA SALLE, COLORADO.

MUSIC-LEAF TURNER.

1,248,692.

Specification of Letters Patent.

Patented Dec. 4, 1917.

Application filed July 11, 1917. Serial No. 179,945.

To all whom it may concern:

Be it known that I, FREDERICK W. MEYER, a citizen of the United States, residing at La Salle, in the county of Weld, State of Colorado, have invented certain new and useful Improvements in Music-Leaf Turners; and I do hereby declare the following to be a full, clear, and exact description of the invention, such as will enable others skilled in the art to which it appertains to make and use the same.

This invention relates to improvements in music leaf turner.

An object of the present invention is to provide a music leaf turner which is of simple, durable and inexpensive construction, is reliable and efficient in use, convenient of manipulation, and furthermore may be manufactured and marketed at a relatively low cost.

A further object of the invention resides in the provision of an appliance of the above character embodying a novel construction and mounting of the leaf carrying elements.

With the above and other objects of similar nature in view the invention consists in the construction, combination and arrangement of parts, set forth in and falling within the scope of the appended claim.

In the drawing:

Figure 1 is a front elevation of a music leaf turner constructed in accordance with the invention, parts being broken away.

Fig. 2 is a vertical section therethrough,

Fig. 3 is a transverse section taken on the line 3—3 of Fig. 1, and

Fig. 4 is a detail perspective view of a pair of leaf carrying elements and their related mechanism.

Referring now more particularly to the accompanying drawing, there is shown a music leaf turner consisting of a main support or board 5 which is preferably of wood and has secured to its front face at its lower end a transverse ledge 6.

Secured also to the front face of the support 5 are a pair of substantially U-shaped bearing plates 7 arranged in vertical alinement and adjacent the upper and lower edges of the support respectively.

A plurality of upper leaf carrying arms 8 are provided and have at their inner ends right angular extensions 9 which are journaled in the upper bearing plate 7, said extensions adjacent the lower leg of said plate

being directed laterally and returned to provide stops 10 the purpose of which will appear.

Encircling each of the extensions between the legs of said plate is a coil spring 11 having its ends secured respectively to the plate and the related stops 10. The normal tending of the springs is to urge the leaf carrying arms in one direction of their movement.

Slidably engaged through the lower bearing plate 7 are a plurality of rods 12 corresponding to the number of leaf carrying arms 8, the same passing also through an angular bearing plate 13 secured to the support between the plates 7 with their upper ends engaged loosely through the lower legs of the upper bearing plate. The rods 12 are furthermore equipped at their lower ends with finger buttons 14 pivoted as at 14' to the board 5 while pivoted thereto between the legs of the lower bearing plate are a plurality of lower leaf carrying arms 15.

At their outer or free extremities the leaf carrying arms 8 and 15 are each provided with a clip 16 by which it is fastened to the music sheet. In order to house the turning mechanism and protect it from injury a cover plate 17 is provided and suitably secured to the support 5.

After connecting the leaf carrying arms with the music sheets as will be readily understood the rods 12 are depressed and said arms swung to the right until stopped by the support 5, so that the springs 11 are placed under tension. The rods 12 are then moved upwardly so that their upper extremities will overlie the corresponding stops 10 and lock the arms 8 against return movement under the influence of the springs 11.

As the score is being played and it becomes necessary to turn the several sheets, the buttons 14 are pressed successively to disengage the rods from the stops 10, the arms 8 being thus free to turn will return to their normal position under the influence of the springs and in consequence turn the music sheets as will be clearly evident.

What I claim is:

A music leaf turner including a support, a substantially U-shaped bearing plate secured to the support, a leaf carrying arm having at its inner end an angular extension journaled in said bearing plate, said

extension between the legs of the plate being provided with a laterally directed stop, a spring encircling the extension with its ends connected respectively with the plate and stop, a rod slidably mounted on the support below said plate, the upper end of said rod passing slidably through the adjacent leg of the plate in position to engage said stop and a second leaf carrying

arm loosely pivoted adjacent the lower end to of said rod.

In testimony whereof, I affix my signature in the presence of two witnesses.

FREDERICK W. MEYER.

Witnesses:

HERBERT A. MEYER,
RUDOLPH E. MEYER.
